DESIGN FOR A DOLL

Mary Wexman, Brooklyn, N. Y.

Application July 11, 1936, Serial No. 63,786

Term of patent 3½ years

To all whom it may concern:

Be it known that I, Mary Wexman, a citizen of the United States, residing at Brooklyn, in the county of Kings, State of New York, have invented a new, original, and ornamental Design for Dolls, of which the following is a specification, reference being had to the accompanying drawing, forming a part thereof, in which—

The characteristic features of my design reside in the two faces and four feet extending in opposite directions of the doll as shown.

I claim:

The ornamental design for a doll, substantially as shown and described.

MARY WEXMAN.
